UNITED STATES PATENT OFFICE.

CHARLES W. GLIDDEN, OF LYNN, MASSACHUSETTS.

LASTING-MACHINE.

SPECIFICATION forming part of Letters Patent No. 251,430, dated December 27, 1881.

Application filed April 30, 1877.

To all whom it may concern:

Be it known that I, CHARLES W. GLIDDEN, of Lynn, in the county of Essex and State of Massachusetts, have invented an Improved Lasting-Machine, of which the following is a specification.

This invention relates to improvements in lasting-machines to last boots and shoes.

One of the most tedious processes in the manufacture of boots and shoes is that of lasting. This has been done by many different kinds of machines, but up to the present time such machines have not fully satisfied their users. This machine employs a set of movable plates for lasting the toe and heel parts, the plates moving over such toe and heel at an angle of about forty-five degrees to a line drawn through the center of the last, and between the toe and heel, at each side, are arranged side-lasting devices, shown as composed of fingers. These fingers are arranged to turn upon their axis, to rise and fall, and to be adjusted horizontally to adapt them to the curve of the last-bottom. The machine in its organization includes a belt or girth adapted to act gradually upon the vamp and stretch and draw it about the last, and co-operating therewith are toe and heel and side lasting devices, adapted to bear the edges of the upper (then stretched about the last and held by the girth or band) horizontally over upon the inner sole. At the commencement of this operation the bottom of the last and the fingers or side-lasting devices and the heel and the toe lasting plates occupy such position with relation to each other that the bottom of the last rests at a level above the level of the said side-lasting devices and toe-lasting plates; but at the completion of the operation the sole occupies a place below the said devices. The girth is so held and operated as to touch the vamp substantially on, at, or near a line drawn from the toe along the vamp, covering the top of the foot portion of the last, (a line denominated by me as the "median line,") and to thereafter bear with greater force upon the said vamp from the said median line to the edge of the last-bottom, thereby gradually drawing the vamp from the said median line toward the edge of and fitting it to the last, after which the edges of the upper, projecting above the last and inner sole, are turned over

upon the inner sole by side-lasting and heel and toe lasting devices.

Figure 1 represents in side elevation a machine embodying my invention; Figs. 2 and 3, end views thereof; Fig. 4, a plan with the side and heel and toe lasting devices at their innermost positions; Fig. 5, a form of arm to support the belt; Fig. 6, a section showing side and shank lasting mechanism; Fig. 7, a detail showing one form of the elastic portion of my belt or girth; Fig. 8, a detail of the device for holding the heel of the upper against the heel of the last; Fig. 9, a detail of cam *h* and disk *i*; and Figs. 10 and 11, forms of belts or girths, to be hereinafter described.

The frame *a* of the machine is of suitable shape to properly sustain the working parts. The driven shaft *b*, operated by a belt upon pulley *c*, has a pinion, *d*, that engages a tooth-wheel, *e*, on the main shaft, which latter rests in bearings *f*, and has attached to it a cam-grooved hub, *g*, a cam, *h*, and a disk, *i*, provided on its periphery with a toe, *j*, and on its face with a pin and roller, *k*. The cam *g* operates the lever *l*, provided with an elongated central slot, *m*, that receives a fulcrum-block, *n*, mounted loosely on a stud, *o*, made vertically adjustable with the block in the slot *p*, to change the fulcrum of the lever *l* and alter the throw of its upper end, and of the sliding head *r*, adjustably connected by the screw *s* with the carriage *t*, which is thus reciprocated by this lever. This carriage *t*, moved in guideways *u*, has a concave upper face, to which is fitted the convex lower surface of a frame, *v*, adjustably attached thereto by set screws *w*. These concave and convex surfaces permit the frame *v*, with its attached devices to last the toe, to be adjusted in the arc of a circle to place the toe-plate 2 in such position with relation to the toe of the last as to move over it, whatever may be its curvature.

The toe-plates are of such shape that when closed their edges conform to the shape of the toe of the last, the plates, when closed, lapping over the last and inner sole. These plates are attached at the ends of levers *x* *y*, the former pivoted at 4 and the latter at 5. The plate of each lever operates upon that side of the toe opposite the side of the toe at which its lever is pivoted. This construction enables the plates to sweep from a point outside the last toward

its center, at an angle approximating forty-five degrees, which permits the upper to be drawn evenly and very close at the toe, and at the sides of the last near the toe, over the edge of 5 the last, thereby drawing in the upper toward the center of the last.

The levers *x y* are connected by links 7 with pins on a hand-lever, 8, having its axis at 9. The links and lever 8 act as a toggle to vibrate 10 the levers to crimp or last the toe. On the axis 9 is an arm, 10, connected by link 11 with a slide, 12, provided with a toe-wiper, 13, preferably of leather or india-rubber. The toe of the last and its upper come to a seat in a toe-rest, 14, provided with a gutta-percha lining, 15, just before the toe-lasting plates 2 are moved 15 forward into the position shown in Fig. 4. After the shoe is lasted the cam *g* and lever *l* act to move the carriage *t* and its attached devices 20 a little in the direction of the arrow, Fig. 4, and then the operator moves the lever 8 and withdraws the toe-lasting plates from the toe, and at the same time the link 11 acts to move 25 forward the toe-wiper 13 beyond the edge of the separated plates 2. Just before the next shoe is to be lasted the carriage *t* is moved forward to place the toe-wiper in line with the toe of the last, so that the upper at the end of 30 the toe will strike against the wiper, and be drawn by it closely and snugly over the last, just before the toe of the last comes into the seat 14, and just before the plates 2 are operated or moved forward to press over the edge 35 of the upper, as before described.

35 By means of the screw *s* the toe-lasting devices may, for lasts of different lengths, be removed more or less from the last-supporting pin. The cam *h* (see Fig. 2) strikes the lower end of the lever 18, carrying the head 19, provided with the longitudinally and vertically 40 adjustable and rocking fingers 20, constituting the side-lasting devices. These fingers are preferably curved, and roughened at their outer ends to engage the upper and retain their engagement with it as they are moved toward 45 the center of the last. Fig. 6 shows a finger and head in end view.

The shank of each finger is fitted to an adjustable holder, 21, where it is confined by a 50 set-screw, 22, the latter permitting the lower face of the finger to be placed at the proper level to correspond with that surface of the last immediately above or over which it is to work. These holders 21 have stems fitted into 55 sockets in the head, where they are adjustably held by set-screws 23, they permitting the fingers to occupy such positions with relation to each other and the surface of the bottom of the last as to conform to the curved and other portions of the last from its toe to its heel.

60 The longitudinal adjustment of the fingers in the holders permits the forward acting edges of the fingers to be placed in a line to conform with the outline of the edge of the last, where- 65 by all the fingers may operate upon the upper simultaneously, or, if desired, sooner at some portions thereof than others. So, too, by ad-

justments of the fingers opposite the shank of the last, they may be made to move to a point nearer the center of the last than the other fingers, thereby facilitating lasting the shank closely, this being of special service when lasting rights and lefts. The opposite head, 24, mounted on lever 25, has a set of fingers like those described as moving with head 19. Lever 25 is vibrated by means of a pin, 17, projecting from the inner face of disk *i*. (See Figs. 2 and 9.) These fingers are not moved horizontally forward to crowd or push the edges of the upper over the edge of the last until after the bottom of the last occupies such a position with relation to the fingers as to be lower than the fingers. Then the fingers close over the last. The notches at the ends of the fingers permit tacks to be driven back from the 85 ends of the fingers. These notches may be of more or less length, long notches being preferably employed in the fingers, especially at the shank, to permit the tacks to be driven back from the center of the shank. 90

The arm 32, having its fulcrum at 33, has its forward end, fore and back part downholds or pressers, 34, 35, shown as adjustably attached thereto, and adapted to bear upon the heel, and the forward or toe portion of the last 95 or inner sole thereon, to seat the last and its upper upon the toe-rest or other support for the last, and place the bottom of the last at the proper level for the correct operation of the side and heel and toe lasting devices. 100 When the carriage is descending and the bottom of the last and side-lasting devices are being brought to such level as to permit the side-lasting devices to be moved horizontally over and beyond the edge of the last and toward 105 its center, the arm 32 is held rigidly by the pawl 36, it then engaging a notch, 37, in a link, 38, connected with a stud or pin, 39, fitted in a slot, 40, at the rear end of arm 32, the opposite end of the link being connected with a 110 hand-lever, 42, moved in one direction by a spring, 43. The arm 32, held rigidly, causes the fore and back part pressers or downholds 34 35 to press upon and position the bottom of the last. After the side-lasting devices have 115 completed their inward movement a pawl-lifter, 44, frees the pawl 36, permitting the spring 43 to throw back the lever 42 and the stud 39 from above the bracket 41. At this stage of the operation the parts are as in Fig. 3. Rotation of the main shaft from the position shown in Fig. 3 will draw the side and the toe lasting devices away from the last and upper and lift the carriage, it carrying with it the jack 45, having a lever, 46, pivoted to it at 47. 120

The lever 46 is provided with a hinged last-holding pin, 48, (shown in dotted lines Fig. 2,) which is held upright by a spring, 49, pressing upon a head-piece forming part of the pin 48 below its pivot. As the carriage and jack are 125 lifted the last is also lifted above the side and the toe lasting devices, and the arm 32 is then thrown over backward on its pivot 33, when the last may be removed and another shoe and

last be substituted for it. A screw, 50, on the jack permits the adjustment of the lever 46 thereon to place it and the last-holding pin at the proper position with relation to the heel-lasting devices, to thus compensate for variations in position with relation to the heel of the last of the hole made therein for the reception of the last holding pin.

The jack 45 is supported upon a rod, 51, provided at bottom with a screw-thread, 52. The screw-thread 52 is engaged by an inclined screw-thread of a bevel-pinion, 53, which is engaged by a bevel-gear, 54, on a shaft, 55. The shaft 55 is adapted to be operated by hand to 15 rotate the pinion 53 when it is desired to raise or lower the rod 51 and place the top of the jack-lever 46 and the last thereon at the proper height with reference to the devices to operate upon the edge of the upper. A slide, 56, is lifted 20 by the toe *j*, (see Fig. 1,) and acts against the end of an adjustable screw, 57, of the jack, just as the side, heel, and toe lasting devices are fully contracted, to lift the jack a little and press the turned-over edge of the upper and inner sole and last closely together, a portion 25 of the cam-groove in the cross-head 28 affording sufficient space to permit the movement of the carriage upward independently of the roll *k*.

A bracket, 58, on the carriage 29, has pivoted to it a lever, 59, provided at its top with a concaved seat, 60, to which is fitted a block, 61, having pivoted arms 62 63, provided with heel-lasting plates or slides 64 65, adapted to operate with reference to the heel, substantially as described, of plates 2 in connection with the toe. These pivoted arms 62 63 are provided with friction-rollers 64, that act upon inclines 65 on the heads 19 and 24, when they are closed, and while the lever 59 moves in the 40 direction of the arrow in Fig. 1, thereby operating the arms and moving the plates against the edge of the upper at the heel, so as to turn such edges over at that point. As the carriage rises the lower end of the lever 59 passes above 45 the roller 66, and the spring 67 moves the lever 59 and the heel-lasting portions away from the heel of the upper and last, to permit the removal of the last and shoe. As the carriage descends, the inclined outer surface of the lever 59 also meets the roller 68, and it and the roller 66 force the lever forward, so that a heel-holder, 69, composed of a piece of metal curved to the shape of the heel end of the last, and connected with a piece of rubber, 70, is pressed 55 closely against the upper on the heel of the last just before or as the toe of the vamp or uppers is being wiped or rubbed by the toe-wiper, and just in advance of the action of the heel-plates 64 65. These pieces 69 70 act to hold the upper in place at the heel.

The upper, about the top of the foot part of the last, is operated upon and laid closely against the last, commencing at the aforesaid median line drawn through the last by means 65 of a band or girth composed of inelastic portions 91, (shown most clearly in Fig. 11,) which during the lasting operation are supported or

kept pressed closely in contact with the upper on the last by a portion, 71, herein shown as composed of india-rubber of suitable shape to 70 assist in pressing the inelastic portions 91 against the upper as the last is forced down by the downholds or pressers acting on the inner sole on the bottom of the last. The inelastic portions 91 are so shaped and held as to first 75 come in contact with the upper on the last substantially at or near this median line, and then to gradually move along over and stretch and press and draw and fit the upper closer and closer to the last, drawing it from the median 80 line toward the opposite edges of the inner sole, and holding it until after the action of the side-lasting devices upon the edge of the upper, they sliding over the last opposite and at or near the end of the girth, it terminating at or near 85 the level or line of action of the side lasting devices.

Fig. 11 shows in elevation a form of girth which I prefer to use. The said girth is shown as composed of a yielding portion, 71, and of 90 portions 91, of leather, canvas, or practically inelastic material, to bear directly against the upper.

The operation of the inelastic portions will be substantially the same when supported at 95 their under sides upon the elastic portion 71, shaped as shown in Fig. 7, as I have practically used in lasting shoes an elastic portion of the form shown in Fig. 7. The inelastic portion of my girth (shown in Fig. 11) bears on a long area 100 of the upper, against which it presses and drags as the inelastic portion is drawn along with reference to the upper, and it thus develops an amount of friction and consequent drawing and stretching on the upper which it could not attain if it touched only at one point or over a short area, while at the same time the constant pressure which it exerts over the whole length of both its elastic and inelastic portions continually presses the upper against the last, and prevents the upper from slipping back, by accident or otherwise, and losing the stretch so obtained. The force of the friction exerted by the inelastic portions of the girth is measured by the upward pressure of the support on which 110 the said inelastic portions rest, or the elasticity 115 of the elastic portions of the girth.

Fig. 7, in end view, shows the elastic portions 71 of a belt or girth stretched across hinged arms 72, which may be provided each with a 120 pivoted dog, 73, as in Fig. 7, or with a roller, 74, as in Fig. 5. Fig. 10 shows a modified form of girth which I devised, but do not herein claim, as I have made it the subject-matter of another application divided off from this one, 125 and filed June 6, 1879.

The central portion, 90, of this girth, Fig. 10, is thickened transversely to bear against the upper on the top part of the last, the girth being too thick to stretch at its central portion. 130 The fore or back part pressers or downholds, being independently adjustable, both vertically and horizontally, enable the heel and toe of the last of any shape or size to be placed at the ex-

act level with relation to the side-lasting and heel and toe lasting devices. The arms carrying the toe-plates or toe-lasting devices would be operated at suitable times.

5 In the operation of this my present machine it will be noticed that the bottom of the last, at the commencement of the lasting operation, occupies a certain relative position with relation to the side and the toe lasting mechanisms or devices, and that at or near the completion of the stretching and drawing operation of the inelastic portions of the girth upon the upper the bottom of the last occupies a different relative position therewith—viz., a 15 position such that the side-lasting devices and heel and toe lasting devices are above the plane of the bottom of the last, and the last is automatically and mechanically held in a fixed position at the level predetermined for 20 it to occupy before the side-lasting devices or toe and heel lasting devices operate to lay the edges of the upper over upon the inner sole on the bottom of the said last.

I am aware that a sole-shaped plate held at 25 or near its center has been laid upon the inner sole on the last, and by a foot-operated treadle has been made to bear the last and upper thereon down while being lasted, so I do not claim a presser or hold-down, except when each 30 is made separate from the other, and each bears only upon a small portion of the inner sole before and back of its shank.

I am aware that lasting-machines were made by Shailer and Ethridge in 1862 and 1863, 35 which machines were put in evidence in the interference case wherein myself and said Shailer and Ethridge were parties, and I do not claim the things contained in said machines which were introduced in evidence in 40 that interference case, such things being public property; but

I do claim as follows, viz:

1. In a lasting-machine, the combination, with devices to last the sides of a boot or shoe, 45 of heel and toe lasting plates pivoted at opposite sides of the line from which the plates approach each other, and adapted to be reciprocated in a path in an angle of about forty-five degrees to a line drawn through the center of 50 the last from heel to toe, whereby the upper at the heel and toe is crowded or pushed over uniformly from the outside of the upper toward the center of the last, substantially as described.

55 2. In a lasting-machine, the combination, with side-lasting devices, of a belt or girth adapted to bear upon the vamp, and by its inelastic portions to stretch and draw the upper to the last, as the relative position of the last-bottom and the side-lasting devices is changed 60 vertically during the lasting process, substantially as described.

3. In a lasting-machine, the combination, with side-lasting devices and horizontal reciprocating heel and toe lasting slides or plates, 65 of a girth or band adapted to operate upon

the vamp to stretch and draw it about the last, substantially as described.

4. In a lasting-machine, a girth adapted to bear against the upper to yield at or near the 70 median line of the upper and by its inelastic portion to press and draw the upper over the sides of and fit it to the last, substantially as described.

5. A girth with its upper end held substantially at the level or line of action of the side-lasting devices, combined with a last and with independent fore and rear part downholds or pressers to hold the inner sole and the last at 80 or near each end of the last while the girth 85 draws the upper and fits it to the last.

6. In a lasting-machine, the last and its support and the independent separate fore and back downholds to hold the inner sole upon the last and cause the last to assume and maintain 85 its proper position vertically with relation to the horizontal or closing-in movement of side-lasting devices during the time the upper is being acted upon by the belt or girth, combined with a girth adapted by its inelastic portions to bear upon and stretch and draw the 90 upper closely about the last during the lasting operation, substantially as described.

7. In a lasting-machine, fore and rear part downholds or pressers, a last, and a girth 95 adapted to bear upon and stretch and draw the upper about the last as the last and girth by their change of position vertically with relation to each other are forced in close contact, combined with side-lasting devices adapted to be 100 moved horizontally over and toward the center of the bottom of the last to press the edges of the upper extending above the bottom of the last at its sides over upon the inner sole upon the last, substantially as described. 105

8. In a lasting-machine, a rigid head, 19, a series of side-lasting devices and their vertically-adjustable holders 21, the side-lasting devices being held in the holders, so that they may be oscillated as required to permit some 110 of the said side-lasting devices at the side of the last to be adjusted to different heights and inclinations to conform to the variations in the curvature of the bottom of the last, substantially as described.

9. Vertically-adjustable fingers adapted to be moved horizontally over the last-bottom, in combination with a girth to operate upon the vamp or fore part of the upper and stretch it about the last, substantially as described. 115

10. In a lasting-machine, a series of adjustable fingers adapted to conform to the last-bottom, and mechanism to move them, in combination with heel and toe lasting plates and with a girth to fit the upper about the last, 120 substantially as described.

11. The combination, with toe-lasting plates, of a toe-wiper, to operate substantially as described.

12. The lasting-plates 2, in combination with 130 their carrying-arms, having their pivot on opposite sides of the line from which the plates

- approach each other to turn over and crimp the stock, substantially as described.
13. In a lasting-machine, two independent adjustable fore and rear part downholds or 5 pressers to bear upon the inner sole each side its shank toward its toe and heel, and a girth or belt having independent inelastic portions which, when pressed against the upper, act by their friction thereon as they are dragged over 10 the upper to draw and stretch the upper from its median line toward the edges of the last and by their contact with the upper retain it stretched while the edges of the upper are being turned over upon the inner sole.
14. In a lasting-machine, heel and toe lasting 15 devices and independent pressers or downholds to bear upon the inner sole on the bottom of the last, and a girth or belt having independent inelastic portions adapted, when pressed against 20 the upper on the last and dragged over the upper from its median line in each direction toward the sides of the last, to draw and stretch the upper about the last, substantially as described.
15. In a lasting-machine, pressers or down- 25 holds to rest upon the fore and back part of the last, and mechanism to automatically force them down while fitting the upper about the last.
16. In a lasting-machine, a girth adapted to 30 bear upon and stretch and draw the upper about the last, and a support to which the upper end of the girth is secured at or below the line of movement of the side lasting de- 35 vices, and side-lasting devices to operate substantially as described.
17. In a lasting-machine, fore and back part 40 pressers or downholds to bear upon the inner sole upon the last, and a pin to support the last, combined with devices to grasp the heel of the upper, and heel-cramping plates or slides, made vertically movable therewith with relation to the toe and the side lasting devices, substantially as described.
18. In a lasting-machine provided with a 45 girth and with side and heel and toe lasting devices, mechanism to move the inner sole and last and side-lasting devices vertically with relation to each other after laying the edges 50 of the upper over upon the inner sole, to thereby press the said turned-over edges of the upper closely down upon the inner sole while the upper and inner sole are being secured together, substantially as described.
19. In a lasting-machine, automatic devices 55 for forcing a last downwardly with relation to side and toe lasting devices, combined with a girth to stretch and draw the upper about the last preparatory to turning its edges over upon 60 the inner sole.
20. Rigid heads 19 and 24, combined with 65 removable fingers or side-lasting devices and a girth, the fingers being adapted to crowd over the edges of the upper after the latter has been fitted to the last by the girth.
21. In a lasting-machine, rigid heads 19 24, side-lasting fingers carried by and moved horizontally in unison with the said heads, and made independently adjustable transversely to the width of the last to permit some of the 70 fingers to approach nearer than others to a center line drawn horizontally from the heel to the toe of the last.
22. The lever 59, inclined at one edge, in combination with a roller, 68, to crowd the 75 heel-lasting devices forward, substantially as described.
23. The jack and last and toe and heel lasting devices, in combination with mechanism to automatically lift the last after turning the edge 80 of the upper over upon the inner sole, substantially as described.
24. The combination, with the vertically-movable carriage, jack, and last, of a last-positioning lever provided with downholds 34 35, 85 to bear on the inner sole as the carriage descends, substantially as described.
25. In a lasting-machine, a jack provided with a pin to enter an opening in the heel of and to support the last, combined with a rear- 90 part downhold to bear upon the inner sole near the heel of the last, preparatory to the action of the toe-support and toe-lasting devices upon the upper and last at or near the toe thereof, substantially as described. 95
26. A pivoted last-pin to enter a hole made at the heel end of the last, and mechanism to bear the heel portion of the upper against the heel of the last, combined with a downhold to operate upon the inner sole at the heel end of 100 the last and maintain the last-bottom at the proper level preparatory to the action of the toe-support upon the toe of the last, substantially as described.
27. In a lasting-machine, inelastic or leather 105 portions, substantially as described, adapted by their friction on the upper about the top of the foot of the last to stretch and draw the upper closely about and fit it to the foot part of the last, toe-lasting plates, independent fore 110 and rear part downholds, and a toe-wiper to act upon the upper at its toe and wipe or draw it over the toe of the last, substantially as and for the purpose described.
28. The fore-part downhold to operate on 115 the inner sole on the last, and toe-lasting devices to act upon and turn over upon the inner sole the toe of the upper, as described, combined with a toe-wiper and means to actuate the same positively in the direction of the 120 length of the last, for the purposes substantially as set forth.

In testimony whereof I have signed my name to this specification in the presence of two subscribing witnesses.

CHARLES W. GLIDDEN.
